UNITED STATES PATENT OFFICE.

RICHARD TANNER, OF LINCOLN, NEBRASKA.

AUTOMATIC REGISTERING DEVICE.

No. 878,835.

Specification of Letters Patent.

Patented Feb. 11, 1908.

Application filed March 23, 1907. Serial No. 364,120.

To all whom it may concern:

Be it known that I, RICHARD TANNER, a citizen of the United States, residing at Lincoln, in the county of Lancaster and State of Nebraska, have invented certain new and useful Improvements in Automatic Registering Devices; and I do hereby declare the following to be a full, clear, and exact description of the invention, such as will enable others skilled in the art to which it appertains to make and use the same.

My invention relates to automatic registering devices and more particularly to that class adapted to be used in connection with repeating firearms and my object is to provide means for indicating the number of cartridges remaining in the magazine of the firearm.

A further object is to provide means for automatically operating the indicator with each reloading of the firearm.

Other objects and advantages will be hereinafter referred to and more particularly pointed out in the claims.

In the accompanying drawings which are made a part of this application, Figure 1 is a perspective view of a portion of a repeating rifle showing my improved indicator secured thereto. Fig. 2 is a vertical sectional view as seen on line 2—2 Fig. 1. Fig. 3 is an elevation of the indicator on an enlarged scale showing the dial removed and parts of the device in section, Fig. 4 is a detail sectional view on an enlarged scale as seen on line 4—4 Fig. 3. and, Fig. 5, is a perspective view of a portion of a repeating rifle, parts thereof being shown in sections.

Referring to the drawings in which similar reference numerals designate corresponding parts throughout the several views, 1 indicates the stock of a rifle to which is secured a barrel 2, said stock and barrel constituting the usual well known form of repeating rifle, a magazine 3 being secured to the under side of the barrel to receive the usual form of cartridge used in connection with a rifle. In firearms of this class, that portion of the stock immediately in the rear of the breech of the gun is provided with a cavity 4 in which is located the usual form of loading block 5, which normally rests in the lower portion of the cavity and is provided with a slot 6 which is adapted to register with the opening in the magazine when the block is in its lowered position so that the cartridge expelled from the magazine will rest in the slot

and be in line with the bore in the barrel when the loading block is elevated.

The loading block 5 is adapted to be elevated in any preferred manner as by the 60 operation of swinging the trigger guard 7 downwardly and forwardly, said trigger guard being connected to the loading block by means of the usual form of swinging finger 7^a, and as the trigger guard is lowered 65 the breech pin 8 is moved longitudinally out of the cavity 4 thereby permitting the loading block to move upwardly in the cavity until the cartridge in the slot 6 is disposed between the breech pin 8 and the bore in the 70 barrel, when by returning the trigger guard to its initial position, the breech pin will again be moved into the cavity and the cartridge forced into the bore of the barrel when the loading block 5 will again descend 75 to its initial position and receive another cartridge from the magazine.

In hunting certain classes of large game it is always desirable to know the number of cartridges remaining in the magazine as it 80 frequently happens that the hunter is required to fire several shots at close range and whose life depends upon having a sufficient number of cartridges to slay the animal before reaching the hunter and to this end I 85 have provided my improved form of register which consists of a casing 9 which is secured to a plate 10, said plate being provided with a plurality of bores 11 to receive screws 12, the inner ends of said screws being adapted 90 to engage bores in the metal portion of the stock 1 to secure the casing thereto.

The casing 9 is preferably cylindrical and provided adjacent its outer edge with a circular ledge 12^a on which is adapted to rest a 95 dial 13. The dial has secured to its inner surface and preferably integral therewith a ratchet wheel 14 through the central portion of which and the dial 13 is directed a pivot pin 15, the inner end of said pivot pin finding 100 a bearing in the central portion of the plate 10, the pivot pin when engaging the plate serving to hold the dial in position on the ledge.

In order to automatically operate the dial 105 and cause the same to positively rotate in one direction I pivotally mount within the casing 9 and upon the plate 10, a rocking beam 16, said beam extending an equal distance to each side of its pivot point 17 and 110 has secured to one end thereof a pawl 18, the free end of the pawl being adapted to en-

gage the ratchet wheel and cause the same to rotate when the beam 16 is rocked.

The opposite end of the beam 16 has secured thereto a pitman 19, the free end of which is disposed through a sliding block 20, the extreme upper end of the pitman being enlarged and tapered on its inner face as shown at 21, with which is adapted to engage the tapered end 22 of a plunger 23.

10 The plunger 23 extends at right angles to the pitman 19 and is longitudinally movably mounted in a socket 24 which is in turn entered through a bore 25 in the plate 10. The extreme inner end of the plunger 23 is also tapered to engage a beveled section 26 on the outer face of one wall of the loading block 5 so that when said loading block is elevated, the plunger will be moved inwardly into engagement with the tapered 20 end of the pitman 19 and the plunger 23 is held against rotation and held into engagement with the pitman 19 by means of a spring finger 27, one end of which is fixed to the plunger and the opposite end thereof to the plate 10.

15 When the pitman 19 is given a longitudinal thrust to rock the beam 16, the pawl 18 will rotate the ratchet wheel 14 and dial secured thereto a certain distance and in order to re- 30 turn the pawl, rocking beam and pitman to their initial positions, I provide a notch 28 in one edge of the pawl 18 in which is entered one end of a spring arm 29, that portion of the spring arm engaging the notch being at 35 right angles to the body portion of the spring arm and the two parts are connected together by a spiral section 30 while the upper end of the spring arm 29 is looped around a stud 31 on the plate 10, the extended end 32 of the spring arm engaging a dog 33 which is pivoted to the plate 10 and adapted to engage the ratchet wheel 14 to prevent a rearward movement of the same when the pawl 18 is returned to its initial position, the engagement of the extended end 32 with the dog, holding the spring arm into engagement with the pawl while the engagement of the spring arm with the pawl holds the extended end into engagement with the dog.

40 The outer face of the dial 13 is provided with a plurality of numerals 34 equal in number to the number of cartridges held by the magazine 3. The dial is also provided with a designating zero which indicates when the magazine is empty and with a letter F to show that the magazine is full and when the magazine is filled with cartridges, the dial is manually rotated until the letter F is in registration with an index point 35 from which 45 position each removal of the cartridge from the magazine will be indicated.

45 In operation when the loading block 5 is elevated to dispose the cartridge in position to be entered in the bore of the barrel, the 50 beveled section 26 will engage the tapered

end of the plunger 23 and force the same outwardly, the tapered end 22 of the plunger engaging the tapered end of the pitman 19 and forcing the same downwardly which will result in rocking the beam 16 and cause the 55 pawl 18 to rotate the ratchet wheel and dial a predetermined distance which reading from the outer face of the dial would be from F to 1, thereby indicating that one cartridge had been removed from the magazine and this 60 operation is repeated until the dial has made a complete rotation and the zero registered with the index point 35 which would indicate that the magazine was empty.

65 Should the magazine be partially emptied and a new supply of cartridges placed in the magazine but not enough to entirely fill the same, the dial may be readily set to indicate the exact number of cartridges in the magazine has, for illustration, should the number 70 11 register with the index point 35 it would indicate that there still remained within the magazine three cartridges and should six additional cartridges be placed in the magazine, the dial should then be rotated until the 75 numeral 5 registers with the index point 35, thereby indicating that there were nine cartridges in the magazine assuming of course, that the magazine holds 14 cartridges.

80 It will thus be seen that I have provided a very cheap and economical means for indicating the number of cartridges in the magazine of the gun and one that can be applied to use in connection with any form of repeating firearm employing a loading block for 85 elevating cartridges from the magazine to the bore in the barrel.

85 It will also be seen that the dial may be readily set to indicate any additional number of cartridges placed in the magazine 90 when the magazine is partially empty and while I have shown and described the indicator as used in connection with a repeating rifle, it will be understood that the same may be used in connection with repeating shot 95 guns with equal success.

95 What I claim is:

1. The combination with a fire arm, having a magazine, a loading block and means to raise and lower said loading block; of a 100 dial, means to mount said dial on the fire arm and a movable connection extending from said dial and in the path of said loading block, whereby the dial will be rotated a pre-determined distance with each upward 105 movement of the loading block.

110 2. The combination with a firearm, having a magazine, loading block and means to operate said loading block; of a dial, means to mount said dial on the firearm, a plunger, one end of which is in the path of said loading block and means engaged by the opposite end of said plunger to rotate said dial a pre-determined distance in one direction.

115 3. The combination with a firearm hav-

120 125 130

- ing a loading block and means to raise and lower said block; of a dial having a plurality of indicating characters on the face thereof, a housing for said dial, means to rotatably 5 secure said dial to the firearm, a ratchet wheel integral with said dial and means interposed between said ratchet wheel and loading block to rotate said dial a predetermined distance when the loading block is raised.
- 10 4. The combination with a firearm having a loading block, and means to operate the same; of a dial having a plurality of designating characters thereon, a casing for said dial, means to rotatably mount the dial upon the firearm, a ratchet wheel integral with 15 said dial, a plunger, one end of which is disposed in the path of the loading block, a pitman slidably mounted in said casing and adapted to be engaged by the opposite end 20 of said plunger and means between the free end of said pitman and the ratchet wheel to rotate said dial a predetermined distance when the plunger is directed into engagement with the pitman.
- 25 5. The combination with a firearm; of a dial, a casing for said dial, means to rotatably mount the dial in the casing, a ratchet wheel on said dial, a plunger, means between one end of said plunger and the ratchet wheel to 30 rotate said ratchet wheel and dial a predetermined distance and means carried by the firearm to engage said plunger and move the same longitudinally whereby the means between the plunger and ratchet wheel will be 35 operated and the dial rotated.
6. The combination with a firearm having a magazine to hold cartridges and means to convey the cartridges from the magazine to the exploding chamber of the firearm; of a 40 dial rotatably mounted on said firearm, a ratchet wheel integral with said dial, a
- plunger, a pawl for said ratchet wheel, means to hold said pawl into engagement with said ratchet wheel, operating means between said pawl and plunger to move said pawl longitudinally when the plunger is operated, one end of said plunger being in the path of the cartridge conveying mechanism whereby the dial will be rotated a predetermined distance with each conveyance of a cartridge from 45 the magazine to the exploding chamber.
7. The combination with a firearm having a magazine and an exploding chamber and means to convey cartridges from the magazine to the exploding chamber; of a 50 dial having a plurality of designating characters on the face thereof, means to rotatably mount said dial on the firearm, a ratchet wheel on said dial, a rocking beam pivotally mounted below said dial, a pawl at one end 55 of said rocking beam, means to direct the free end of said pawl into engagement with said ratchet wheel, a pitman at the opposite end of said rocking beam, said pitman having a tapered upper end, a plunger, each end of 60 which is tapered, one end of said plunger being adapted to engage the tapered end of the pitman, means to hold said plunger against rotation, the opposite end of said plunger extending into the path of the cartridge 65 conveying means whereby the dial will be moved a predetermined distance with each operation of the conveying mechanism and means to hold the dial against inverse rotation.
- 75 In testimony whereof I have signed my name to this specification in the presence of two subscribing witnesses.
